UNITED STATES PATENT OFFICE

RICHARD VON REPPERT, OF HARTFORD, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed November 21, 1927. Serial No. 234,819.

My invention relates to power-driven typewriting machines, and more specifically to that class of machine where a power-rotated electromagnetized cylinder creates a magnetic field co-operating with a type-bar-actuating pendant through the attractive force and the coefficient of friction, one to the other, following the partial depression of the associated character-keys.

10 In my application No. 219,607, filed September 15, 1927, the partial depression of each key-lever shifts a pendant pivotally attached thereto into the magnetic field of the rotating cylinder that operates to finish the 15 stroke of the key-lever by power to project the connected type-bar to the typing position.

My application, No. 221,451, filed September 23, 1927, provides a key-lever, a type-bar-actuating lever and an intermediary member 20 having an interruptive connection with the key-lever and a driving connection with the type-bar-lever, whereby the depression of a key shifts the intermediary member into the rotary magnetic field of the cylinder to be 25 actuated by the latter to throw the type-bar independently of the key-lever, and permit the return of the key-lever independently of the typing movement.

My present invention provides a structural 30 combination for the rotating cylinder and reciprocable armature, whereby mechanical clutching faces are brought into co-operative pressed-together relation through the magnetic attraction of the cylinder, and are rendered effective by a greatly reduced magnetism for the rotating cylinder to actuate the 35 type-bar to type, as distinguishable from my two prior applications, where electromagnetic attraction wholly supplies the clutching power between flat coating faces of both 40 cylinder and armature.

To this end, the magnetic cylinder is provided with V-shaped peripheral grooves, one groove for each intermediary, and each intermediary having a corresponding V-shaped cross-section. The two V-shaped members, nesting one within the other, present an effective mechanical clutching combination that is operative under a nominal pressure supplied by electro-magnetism is especially

adaptable to the condensed assembly of the pendent armatures, where the allotted working space is less than three-sixteenths of an inch between centers, most effective for increasing the armature-driving power derived from the cylinder, and operates with a substantial reduction of magnetic force and a corresponding reduction in the consumption of electric current.

55 The principle involved for this mechanical clutching organization is similar to the well-known V-groove form of power-transmission from interlocking wedge-faced or tapering friction-wheels, which are conceded to produce the greatest resistance against slipping with a minimum of applied pressure, when an interruptive, silent and smooth transmission of power is desired.

60 In the present instance, the tangential force transmitted to the pendent armatures by the wedging or clutching action of the rotary cylinder is equal to the product of the applied pressure and the coefficient of friction between the tapering grooved faces of the cylinder, where each face has an established 65 inclination of approximately seven degrees, or an included angle of fourteen degrees, for the coating armature-faces, and which combination ordinarily provides for the disengagement of V-clutching faces without undue 70 sticking or cohesion when applied pressure is removed from them.

75 Other features and advantages will hereinafter appear.

80 In the accompanying drawings,

85 Figure 1 is a central, vertical section through an Underwood standard typewriting machine, showing only such parts of the typewriting mechanism necessary to co-operate with the power-driven mechanisms forming the subject-matter of this invention.

90 Figure 2 is an enlarged view, in perspective, of the extreme left-hand key of the keyboard and its connecting and operating parts that co-operate with the power-driven magnetized cylinder.

95 Figure 3 is a diagram of the circuits that include a motor-starting switch and a rheostat in the cylinder-circuit to regulate the 100

degree of magnetism for the power-driven type-bar-actuating cylinder.

Figure 4 is a partial front elevation in vertical section, the sectional plane of the 5 left-hand half of the figure being taken in front of the lower bank of keys, and the plane of the right-hand half of the figure being taken just in front of the driving cylinder.

Figure 5 is an enlarged view in section, 10 showing the intermediary or armature in clutching engagement with a corresponding friction-groove in the driving cylinder.

Figure 6 is an operational view, showing 15 a key depressed against a stop to vibrate an intermediary member into the magnetic clutching field of the rotating magnetized actuator, which, in rotating in the direction of the arrow, has drawn the intermediary downward and the connected parts have 20 conveyed movement to the type-bar to raise the latter to the full-line position in front of the platen, at which position the nonmagnetic cam-face of said intermediary is about to perform its function of separating the armature from the magnetic control of the 25 rotating cylinder.

Figure 7 is a fragmentary view of Figure 30 6, showing the intermediary or armature carried down from the position of Figure 6 to a point where the nonmagnetic cam has 35 swung the intermediary outside the magnetic field of the rotating cylinder, which shifts the type-bar to the dotted position of Figure 6, and, from which dotted position, the type-bar will swing to the platen, under its own momentum, to type.

Figure 8 is an enlarged view of a novel 40 manner for adjustably securing the backing-up and intermediary separating or spacing comb at each end to the frame of the machine.

For the purpose of the present invention, the usual Underwood key-levers are superseded by keyless levers 10, fulcrumed at their 45 rear ends to a bar 11, and provided with individual springs 12, operative to normally hold each lever against the stop-face of a front-spacing comb 13, extending transversely over said levers to guide and maintain 50 their parallelism at the front ends thereof. Each lever 10 has a driving stud 13^a, operative within a slot 14 of the short arm 15 of a bell-crank 16, vibrating about a fulcrum-rod 17 when the lever 10 is vibrated. The 55 long arm 18 of each bell-crank carries a driving stud 19 at the upper free end, that releasably interlocks with a slot 20 formed in a type-bar 21, that swings about a curved fulcrum-wire 22 to register the type-faces at 60 a common typing point on the platen 23 at each depression of the lever 10. The upward and rearward swing of each type-bar 21, just in advance of the typing position, collides with a universal bar 24, swingable rearward- 65 ly to vibrate the usual carriage-feeding

mechanism 25 to letter-feed the carriage at each typing movement. The platen 23 is rotatably mounted in a carriage 26 that travels in a letter-space direction upon rails 27, under the influence of a spring-motor 28, connected 70 by a tape 29 to the carriage in the well-known Underwood manner.

Adjacent the front end of each lever 10 and just in front of the comb 13^a, a soft permeable armature or intermediary member or 75 coupler 30 hangs pendent therefrom upon a well-known form of supporting pivot 31, that provides eccentric adjustment for the armature of each lever 10 with means for locking the adjusted relations thereof, and providing 80 a free swinging movement for the armature.

The cylinder 32 may be constructed along the lines described in my prior application, No. 219,607, where disk-sections 33 are assembled end to end upon a driving shaft 34, and each disk formed with compartments 35 for housing coil-units 36 having their terminal-wires joined in series through the cylinder to form a continuous circuit between commutator-rings 37 secured to the shaft 34 at each 90 end of the assembled cylinder 32. Alternate coils 36 are wound in opposite directions to alternately change the polarity of the assembled disks 33. Each ring 37 may have a brush 38 supported by and insulated from the frame of the machine and wired to a motor-circuit in such a manner that the starting of a motor 39 will simultaneously close the circuit through the series of coils to magnetize the cylinder as a unit, and the motor through a worm-and-gear connection 100 40 will simultaneously rotate the driving shaft 34, and the cylinder becomes a rotating magnetized body to co-operate with the pendent armatures 30 for depressing the levers 10 to actuate their type-bars.

In my prior applications, previously mentioned, in vibrating the armatures into the magnetic field of the rotating cylinder, the armatures presented flat faces for coaction with the flat circular face of the magnetized cylinder, and, as the width of each armature-face was limited to less than three-sixteenths of an inch, which may be a standard spacing of the levers 10, inadequate armature-face area and excessive current for the coils might be required to establish sufficient gripping or attractive power to convey motion from the magnetized cylinder-face to the flat face of the armature to reciprocate the latter, and which might result in overheating of the coils. To obviate this trouble, should it be found to exist, it is the purpose of the present improvement to provide a tongue and groove construction having an armature with a maximum friction face-area and to dispose of this area in such a manner that gripping mechanical clutch-faces are provided for both the armature and for the cylinder, and the magnetic features of the cylinder will only be 110 115 120 125 130

employed to magnetically hold the mechanical clutching faces in operative clutching engagement under pressure by the use of a greatly reduced magnetism in the cylinder 5 and a corresponding reduction in current.

To this end, the edge of each armature 30 that faces the cylinder 32 is formed of a V-shaped cross-section to provide clutching angular faces 41, that provide the armature 10 with a long tooth or tongue that is rideable edgewise across the surface of the cylinder to convey a straight down pull to the levers 10.

Each disk 33 is formed of a central peripheral groove 42 having a contour similar to the contour of the armature, and the edges of each section 33 are chamfered or beveled, as at 43, so that the built-up abutment of two disks, end to end, form a groove similar to 20 that at 42. It will be noted at Figure 5, that each groove 42 may be cut extra deep so as to form a clearance-gap 44 to allow for wear upon the soft faces 41 of the armatures 30.

To accurately align the armatures 30 to the 25 grooves 42 in the cylinder, a bar 45 may be secured to the under edge of each side frame to bridge the two side walls thereof. This bar may be formed with open slots 45^a in one edge to guide and space the lower ends of the 30 armatures 30, the armatures being normally held therein by a suitable spring 46 tensioned between each armature and the free end of its lever 10. Each armature 30 may be further provided with an anti-friction roll 47 mounted 35 within the slots 45^a, and each armature bearing against its roll under the tension of a spring 46. These rolls 47 may be mounted upon a rod 48 set in grooves 49 and held therein by clips 50 secured to the ends of the 40 bar 45.

It is an advantage that the bar 45 be adjustably secured to the frame, so that the rolls 47, as a series, may be advanced or withdrawn from the cylinder to determine a normal 45 position for the armatures that shall be only slightly removed from the magnetic field or attraction of the cylinder, and require little vibratory movement thereof from a key-depression to establish coaction between 50 armatures and cylinder. As shown at Figure 8, instead of securing each end of the bar 45 to the side frame of the machine, brackets 51 may be secured to the side frames to extend inwardly where the free ends are arranged to support the ends of the bar 45. The corners at each end of the bar 45 may be removed to provide a forty-five degree edge 52, and provided with cone-screws 53 threaded 55 into the brackets to bear against the edges 52 and provide a fine displacement of the bar 45, either towards the cylinder to determine the normal position of the armatures, or longitudinally of the cylinder to align the 60 armatures to the groove, these screws serv-

ing as both a bar-shifting and bar-retaining means for each end of the bar 45.

In my aforesaid application, No. 219,607, means are carried by each armature, that become operative during the throw of the 70 armature, to cam the armature by its throw at a predetermined point out of the magnetic field of the cylinder just prior to the typing movement. These means include a non-magnetic cam that becomes an entering 75 wedge between the armature and the rotating cylinder, and, owing to its non-magnetic characteristics, becomes operative to sever the magnetic attraction of the cylinder and co-operate with the cam to release the armature. Similarly, each armature 30 may be provided with a brass or non-magnetic camming insert 54 secured to each armature in any well-known manner, and operative, as 80 already described, to sever the armature from 25 the magnetic or clutching control of the cylinder at the end of a typing operation.

To effect the selective vibration of the armatures 30 into the magnetic field of the cylinder 32, numeral keys 55 and character keys 90 56 are provided with key-levers 57 mounted upon a fulcrum-rod 58 secured to each side wall of the machine-frame, said levers being supported upon the rod by spacing washers 59 which align the keys for a standard key-board-spacing. Each lever 57 may be integrally formed with a pendent arm 60, provided near its lower end with a trip-pawl 61, fulcrumed upon a screw 62, threaded into 95 said arm 60, and formed with an arm 63 normally bearing against a stop-pin 64 under the tension of a spring 65, connecting the free end of the arm 63 with a stop-bar 66, bridging the keyboard and secured at the ends thereof to the side frames. Thus, by a single 100 105 spring 65, the pawl 61 is tensioned against the stop-pin 64 on the arm 60, and key-lever 57 is tensioned against the stop-bar 66. To coact with each pawl 61, a stud 67 projects 110 from the side face of its associated armature 30.

When any key 55 or 56 is depressed, the corresponding movement of the arm 60 swings the pawl 61 into engagement with the stud 67 against the tension of the spring 65. 115 The stud 67, when so driven by the pawl 61, vibrates the armature 30 against the tension of the spring 46. When the armature 30 enters the magnetic field of the cylinder, the magnetic action removes the armature from 120 further control of the pawl 61 by drawing the faces 41 into clutching engagement with the aligned groove 42 in the cylinder. Were the cylinder stationary and the magnetism of the cylinder destroyed, the gripping of 125 the clutching faces under the magnetic impact might be found sufficient to effect the actuation of the lever 10, were the cylinder drawn down bodily in a straight line. The pull upon the armature, however, is a roll- 130

ing pull, and the rotation of the cylinder per se would operate to sever these clutching faces, but the magnetic attraction of the cylinder, which causes the clutching faces to 5 cleave together during the surface changing or rolling contact between the cylinder and the armature, provides a continuous pressure to hold the armature in rolling and clutching engagement, and conveys motion 10 to the armature in a tangential direction aligned to the pivot of the armature upon the lever 10 for a substantially straight down pull. As shown at Figure 6, when the armature 30 has been drawn to the position 15 shown, it will be observed that the non-magnetic cam 54 has cut one-half of the magnetic attraction of the cylinder and is about to cam the armature to sever the remaining clutching forces by the parts assuming the 20 position shown at Figure 7, where the armature has been cammed free from the cylinder and is about to respond to the tension of the spring 46 and be drawn against its roll 47. The type-bar, in the meantime, has been 25 advanced from the full-line position to the dotted position at Figure 6. The momentum of the parts carries the type-bar from the dotted position at Figure 6, to strike the platen and recoil under its impact assisted 30 by the restoring spring 12 of the lever 10.

The key-levers 57 are deppressible against an adjustable stop-bar 68, and, should a key be held depressed against said bar, the restoring movement of the armature 30 will cause the 35 stud 67 to trip by the depressed pawl 61 by flexing the spring 65 and making it impossible to type duplicates from a held-down key-lever.

From this description, it will be noted that 40 this power-driven typing system includes detached key-levers, detached type-bar-operating levers, and intermediary members or couplers, said intermediary members having a driving connection with the type-bar-levers, an interruptive connection with the 45 key-levers, and an interrupted reciprocable connection with a power-driven constantly-rotating electromagnetized cylinder, whereby the depression of a key vibrates the intermediary member into the clutching influence 50 of the rotating cylinder to convey a tangential driving force to said intermediary member, and project the type-bar to the typing position; that the intermediary member 55 is an armature pendently supported by the type-bar-lever and includes gripping wedge-faces mechanically co-operative with corresponding wedge-faces carried by the cylinder, to effect transmittive clutching relations, and magnetically co-operative with 60 said cylinder to maintain a degree of working pressure through magnetic attraction, to render the clutch relations with the cylinder continuous for a predetermined typing 65 period; that the armature-pendants are V-

shaped in cross-section to increase the surface area presentable to the magnetic influence of the cylinder to increase the friction and correspondingly reduce the working pressure derived from the electromagnetized cylinder; 70 that the reduction in the magnetism of the cylinder to reduce the working pressure on the V-shaped armatures correspondingly reduces the current required for the coils that magnetize the cylinder; that the interrupted 75 connection between the key-levers and armatures removes any possibility for multiple typed impressions from a held-down key; and that typed impressions will have a uniform inked density independently of the 80 manner of manipulating the keys.

It will also be noted that the magnetized cylinder 32 becomes a universal rotary friction-clutching member, and that the armature 30 pendent from each key-lever constitutes individual friction clutchable elements cooperative with the cylinder through magnetic attraction, to convert the rotary motion of the cylinder into a reciprocation for any key-vibrated armature to drive a 90 lever to type.

Variations may be resorted to within the scope of the invention, and portions of the improvements may be used without others.

Having thus described my invention, I 95 claim:

1. In a typewriting machine, the combination of a series of type-bars, a series of keys, operating means for the type-bars including a series of couplers, one for each bar, a power-driven magnetized cylinder having peripheral grooves, one groove for each coupler, and each groove having coupler-gripping characteristics re-enforced by the magnetic state of the cylinder, and means 100 operable by the keys and effective to bring each coupler into the magnetic clutching field of a groove to drive the coupler.

2. In a typewriting machine, the combination of a series of type-bars, a series of keys, operating means for the type-bars including a series of couplers, one for each bar, a power-driven magnetized cylinder having peripheral grooves, one groove for each coupler, and each groove having coupler-gripping characteristics re-enforced by the magnetic state of the cylinder, and means operable to selectively and initially force any coupler into the magnetic clutching field of a groove by the keys and effective to drive the coupler and 115 its type-bar.

3. In a typewriting machine, the combination with a series of type-bars, of operating means therefor including a series of couplers, one for each bar, a power-driven shaft having 120 peripheral grooves, one groove for each coupler, and each groove having coupler-gripping characteristics, keys operative to selectively present any coupler to its groove, and means inherent in the shaft effective to 125 130

supply a friction-inducing pressure for any coupler presented to its groove to operate the coupler.

4. In a typewriting machine, the combination with a series of type-bars, of operating means therefor including a series of couplers, one for each bar, a power-driven shaft having peripheral grooves, one groove for each coupler, and each groove having coupler-gripping characteristics, keys operative to selectively present any coupler to its groove, means inherent in the shaft always effective to supply a friction-inducing pressure for any coupler presented to its groove 10 to operate the coupler, and means integral with the coupler and operative by the shaft-driven movement thereof to negative the frictional pressure and release the coupler.

5. In a typewriting machine, the combination with a series of type-bars, of means for operating said type-bars including a power-driven magnetic cylinder, and a series of armature-couplers, one coupler for each type-bar, each coupler having clutching faces to be driven, the cylinder having cooperating driving clutching grooves, one for each coupler, the magnetism of the cylinder effecting a pressing engagement between any coupler and its groove to render the rotating cylinder 25 operative to drive the coupler.

6. In a typewriting machine, the combination with a series of type-bars, of means for operating said type-bars including a power-driven magnetic cylinder, a series of armature-couplers, one coupler for each type-bar, and a series of keys, one key for vibrating each coupler, each coupler having clutching faces to be driven, the cylinder having cooperating driving clutching grooves, one groove 35 for each coupler, the magnetism of the cylinder inducing a pressing engagement between any key-vibrated coupler and its groove, to render the rotating cylinder operative to drive the coupler independently of the key.

45 7. In a typewriting machine, the combination with a series of type-bars, of means for operating said type-bars including a power-driven magnetic cylinder, a series of armature-couplers, one coupler for each type-bar, a series of keys, one key for vibrating each coupler, each coupler having clutching faces to be driven, the cylinder having co-operating driving clutching grooves, one groove for each coupler, the magnetism of the cylinder 50 inducing a pressing engagement between any key-vibrated coupler and its groove, to render the rotating cylinder operative to drive the coupler independently of the key, and means carried by each coupler operative during the 55 cylinder-driven movement thereof, to negative the magnetic effect of the cylinder and release the coupler from its driving means.

60 8. In a typewriting machine, the combination with a series of type-bars, a series of keys, a series of operating levers, one for each 65

bar, and a series of couplers, one for each lever, of a power-driven rotating magnetized shaft having peripheral coupler-gripping grooves, one groove for each coupler, the magnetized state of the shaft being effective to 70 re-enforce the grip on the coupler within a groove when presented by a key to frictionally operate the coupler.

9. In a typewriting machine, the combination with a series of type-bars, a series of operating levers, one for each bar, and a series of couplers, one for each lever, of a power-driven shaft having peripheral coupler-engaging grooves, one groove for each coupler, and means inherent in the shaft operative to 80 press each coupler within its groove and frictionally operate the coupler.

10. In a typewriting machine, the combination with a series of type-bars, a series of operating levers, one for each bar, and a series of couplers, one for each lever, of a power-driven shaft having peripheral coupler-engaging grooves, one groove for each coupler, and means inherent in the shaft operative to 85 engage each coupler into frictional 90 engagement with its groove and convey a rolling tangential type-bar-actuating movement to the coupler.

11. In a typewriting machine having type-bars, the combination of power-driven means 95 to drive the type-bars including a continuously-rotating magnetic universal friction clutch-member, an armature clutch-member connected to reciprocate with each type-bar, keys disconnected from their type-bars but 100 operable to predetermine the clutching engagement between their individual armatures and the universal clutch-member when brought together by magnetism to maintain clutching engagement, and means to disengage the reciprocating armature to release the type-bar to type.

12. In a typewriting machine having type-bars, the combination of power-driven means 110 to drive the type-bars including a continuously-rotating universal friction clutch-member, a normally inoperative individual friction clutch-member connected to each type-bar, keys disconnected from their type-bars but 115 operable to predetermine a clutching engagement between their individual clutch-members and the universal clutch-member to drive a type-bar, magnetic means for at least one clutch-member to maintain a type-bar-driving clutch engagement, and means carried by each individual clutch-member and engageable with the rotating clutch-member 120 to disengage the clutch-members to release the driven type-bar to type.

13. In a typewriting machine having type-bars, the combination of power-driven means 125 to drive the type-bars including a continuously-rotating universal friction clutch-member, a normally inoperative reciprocable individual friction clutch-member connected to 130

each type-bar, keys disconnected from their type-bars but operable to predetermine a clutching engagement between their individual clutch-members and the universal clutch-member to drive a type-bar, magnetic means for the rotating member to maintain a type-bar-driving clutch engagement, and means carried by each individual clutch-member and engageable with the rotating clutch-member to disengage the type-bar clutch-member by its throw and release the driven type-bar to type.

14. In a typewriting machine having type-bars, the combination of power-driven means to drive the type-bars including a continuously-rotating universal friction clutch-member, a normally inoperative reciprocal individual friction clutch-member connected to each type-bar, keys disconnected from their type-bars but operable to predetermine a clutching engagement between their individual clutch-members and the universal clutch-member to drive a type-bar, magnetic means for at least one clutch-member to maintain a type-bar-driving clutch engagement, and a wedge reciprocal with each individual clutch-member and engageable with the rotating clutch-member to separate said members and release the driven type-bar to type.

15. In a typewriting machine having type-bars, the combination of power-driven means including a continuously rotating universal friction clutch-member to actuate the type-bars, an individual friction clutch-member connected to each type-bar, keys disconnected from their type-bars but operable when depressed to predetermine the clutching engagement for each individual clutch-member with the universal clutch-member, magnetic means to maintain the key-set clutching engagement, and means carried by each individual clutch-member operative to disengage the clutch, said last-mentioned means including a wedge-member rendered operative by the throw of the individual clutch-member to be interposed between said individual member and the magnetic means.

16. In a typewriting machine having type-bars, the combination of power-driven means including a continuously rotating electro-magnetized universal clutch-member having a plurality of mechanical clutch-faces to individually actuate the type-bars, an individual mechanical clutch-member connected to each type-bar, and keys operative to selectively bring each individual clutch-member into co-operation with the clutch-faces of the universal member for a type-bar-actuating reciprocal movement, the mechanical clutching engagement between the individual clutch-members and the universal clutch-faces rendered operable through a pressure derived from the magnetic attraction of the universal clutch-member.

17. In a typewriting machine having type-bars, the combination of power-driven means including a continuously rotating electro-magnetized universal clutch-member having a plurality of mechanical clutch-faces to individually actuate the type-bars, an individual mechanical clutch-member connected to each type-bar, keys operative to selectively bring each individual clutch-member into co-operation with the clutch-faces of the universal member for a type-bar-actuating reciprocal movement, the mechanical clutching engagement between the individual clutch-members and the universal clutch-faces rendered operable through a pressure derived from the magnetic attraction of the universal clutch-member, and means carried by each individual clutch-member operable at the end of a type-bar-actuating movement thereof to free said clutch-member from said pressure to release the individual clutch-member and its actuated connections.

18. In a typewriting machine having type-bars, the combination of power-driven means to drive the type-bars including a continuously-rotating magnetic universal friction clutch-member, an individual friction clutch-member connected to reciprocate with each type-bar and engageable with the universal member through mechanical means reinforced by magnetism, keys disconnected from their type-bars but operable when depressed to effect a clutching engagement between each individual clutch-member and the magnetized universal clutch-member, and means reciprocal with its individual clutch-member and operable to remove said member from the magnetic pressure of the rotating member.

19. In a typewriting machine having type-bars the combination of power-driven means to drive the type-bars including a continuously-rotating magnetic universal friction clutch-member, an individual friction clutch-member connected to reciprocate with each type-bar and engageable with the universal member through mechanical means reinforced by magnetism, keys disconnected from their type-bars but operable when depressed to effect a clutching engagement between each individual clutch-member and the magnetized universal clutch-member, and means formed with each individual clutch-member and automatically operable during the type-bar-driving reciprocation of said clutch-member, to wedge said member out of the magnetic grip of the rotating member.

20. In a typewriting machine having type-bars, the combination of power-driven means including a continuously rotating electro-magnetized universal clutch-member having a plurality of mechanical clutch-faces to individually actuate the type-bars, an individual mechanical clutch-member connected to each type-bar, keys operative to selectively

bring each individual clutch-member into cooperation with the universal clutch-member, the mechanical clutching engagement between the individual clutch-members and the universal clutch-faces rendered operable through a pressure derived from the magnetic attraction of the universal clutch-member, and means brought into position to disengage the individual clutch-members from the pressure of the rotating universal clutch-member.

21. In a typewriting machine having type-bars, the combination of power-driven means including a continuously rotating electromagnetized universal clutch-member having a plurality of mechanical clutch-faces to individually actuate the type-bars, an individual mechanical clutch-member connected to each type-bar, keys operative to selectively bring each individual clutch-member into cooperation with the universal clutch-member, the mechanical clutching engagement between the individual clutch-members and the universal clutch-faces rendered operable through a pressure derived from the magnetic attraction of the universal clutch-member, and means brought into position to disengage the individual clutch-members from the pressure of the rotating universal clutch-member, said means including a wedge-member movable with each individual clutch-member to mechanically separate the latter from the universal member.

22. In a typewriting machine having type-bars, the combination of power-driven means including a continuously rotating electromagnetized universal clutch-member having a plurality of mechanical clutch-faces to individually actuate the type-bars, an individual mechanical clutch-member connected to each type-bar, keys operative to selectively bring each individual clutch-member into cooperation with the universal clutch-member, the mechanical clutching engagement between the individual clutch-members and the universal clutch-faces rendered operable through a pressure derived from the magnetic attraction of the universal clutch-member, and means brought into position to disengage each individual clutch-member from the pressure of the rotating universal clutch-member, said means including a non-magnetic member movable with the individual clutch-member and operative to sever said clutch-member from the magnetic clutch of the universal clutch-member.

23. In a typewriting machine having type-bars, the combination of power-driven means including a continuously rotating electromagnetized universal clutch-member having a plurality of mechanical clutch-faces to individually actuate the type-bars, an individual mechanical clutch-member connected to each type-bar, keys operative to selectively bring each individual clutch-member into co-

operation with the universal clutch-member, the mechanical clutching engagement between the individual clutch-members and the universal clutch-faces rendered operable through a pressure derived from the magnetic attraction of the universal clutch-member, and means brought into position to disengage each individual clutch-member from the pressure of the rotating universal clutch-member, said means including a cam-member having non-magnetic characteristics operative during the actuation of said individual clutch-member to jointly sever the magnetic effect of the universal clutch-member and break the mechanical clutch between the clutch-members.

24. In a typewriting machine having type-bars, the combination of power-driven means to drive the type-bars including a continuously-rotating electromagnetized universal clutch-member having V-shaped friction grooves, individual armature-members connected to each type-bar and having a tongue engageable with the V-grooves of said universal member, keys operable when depressed to bring the armature-members into the magnetic field of the universal clutch-member, and means operable to disengage each armature-member at the end of its throw from the magnetism of the clutch-member.

25. In a typewriting machine having type-bars, the combination of power-driven means to drive the type-bars including a continuously-rotating magnetized universal clutch-member having V-shaped friction grooves, one groove for each type-bar, individual armature-members connected to each type-bar and having a V-shaped tongue engageable with the V-grooves of said universal member, keys operable when depressed to effect a clutching engagement between a tongue of the armature-members and a V-groove of the universal clutch-member, and a V-shaped non-magnetic means carried by each armature-clutch member and operative to sever the magnetic grip of said clutch-members by the throw of the armature.

26. In a typewriting machine having type-bars, the combination of power-driven means for driving the type-bars including a continuously-rotating electromagnetized universal clutch-member having V-shaped friction grooves, individual mechanically clutching armature-members connected to each type-bar and having a V-shaped tongue engageable with the V-grooves and thrown by said universal member, keys operable when depressed to effect a clutching engagement between the V-armature-members and the V-grooves of the universal clutch-member, and a V-shaped non-magnetic camming means carried by each armature-clutch-member and operative to sever both the magnetic and the mechanical grip of the universal clutch-member by the throw of the armature.

27. In a typewriting machine, the combination of a printing mechanism, a power-driven member for operating the same, including a V-shaped friction-coupler pivoted 5 to a lever of the printing mechanism and arranged to be thrown by an electro-mechanical friction engagement with said power-driven member, and a key-lever operable when depressed to swing said coupler into the 10 frictional control of said power-driven member, said power-driven member having magnetic characteristics that re-inforce the frictional V-grip of the coupler independently of the key pressure for a typing interval.
- 15 28. In a typewriting machine, the combination of a printing mechanism, a power-driven member for operating the same, including a friction-coupler pivoted to a type-bar lever of the printing mechanism and ar- 20 ranged to be thrown by an electro-mechanical friction engagement with said power-driven member, a key-lever disconnected from said type-bar lever but operable when depressed to swing said coupler into the frictional grip 25 of said power-driven member, said power-driven member having magnetic characteristics that maintain a constant frictional grip of the coupler independently of the key for a typing interval, a cam carried by each cou- 30 pler operative to sever the magnetic grip of the power-driven member at the end of the typing throw of said coupler, and pivotal adjusting means including an eccentric for each coupler effective to determine the typing 35 throw of each coupler.
29. In a typewriting machine, the combination with a series of type-bars, a series of operating levers, one lever for each type-bar, a series of normally-inoperative, attractible 40 couplers, one coupler pivoted to each lever to hang pendent therefrom, a continuously rotating permanently magnetized cylinder, and a series of key-levers, one lever for each coupler and operative to vibrate its coupler into 45 the magnetic field of the cylinder and be driven thereby, of mechanical clutching means for each coupler and for the cylinder that co-operate with the magnetic attraction of the cylinder to drive the coupler and actu- 50 ate a type-bar.
30. In a typewriting machine, the combination with a series of type-bars, a series of operating levers, one lever for each type-bar, a series of normally-inoperative attractible 55 couplers, one coupler pivoted to each lever to hang pendent therefrom, a continuously rotating permanently magnetized cylinder, and a series of key-levers, one lever for each coupler and operative to vibrate its coupler into 60 the magnetic field of the cylinder and be driven thereby, of mechanical clutching means between each coupler and the cylinder brought together and rendered operative by the magnetism of the cylinder, said clutching 65 means including rectilinear wedge-faces for each coupler, and coacting curvilinear grooves for the cylinder.
31. In a typewriting machine, the combination with a series of type-bars, a series of operating levers, one for each type-bar, and a series of normally-inoperative couplers, one coupler secured to each lever, of a power-driven rotatable cylinder having a series of peripheral coupler-engaging grooves, one groove for each coupler, means establishing 70 a permanent magnetic field for the cylinder operative to draw a coupler into gripping engagement with a groove when said coupler is presented to the magnetic field of the cylinder, and means to selectively present said couplers to be engaged and driven by said grooves.
32. In a typewriting machine, the combination with a series of type-bars, a series of operating levers, one for each type-bar, and a series of normally-inoperative couplers, one coupler secured to each lever, of a power-driven rotatable cylinder having a series of peripheral coupler-engaging grooves, one groove for each coupler, means establishing 75 a permanent magnetic field for the cylinder operative to draw a coupler into gripping engagement with a groove when said coupler is presented to the magnetic field of the cylinder, and means to selectively present said couplers to be engaged and driven by said grooves.
33. In a typewriting machine, the combination with a series of type-bars, a series of operating levers, one for each type-bar, and a series of normally-inoperative couplers, one coupler secured to each lever, of a power-driven rotatable cylinder having a series of peripheral coupler-engaging grooves, one groove for each coupler, means establishing 80 a permanent magnetic field for the cylinder operative to draw a coupler into gripping engagement with a groove when said coupler is presented to the magnetic field of the cylinder, and means to selectively present said couplers to be engaged and driven by said grooves, said last-named means including a key-lever and a coupler-vibrating pawl for each coupler.
34. In a typewriting machine, the combination with a series of type-bars, of operating means therefor including a series of friction-couplers, one coupler for each type-bar, and a power-driven cylinder having a pair of peripheral friction-faces for each coupler operative to engage any coupler when presented by the depression of a key, said cylinder having means effective to establish 85 a working pressure operative to render the frictional engagement of the couplers with the cylinder effective to drive the couplers.
35. In a typewriting machine, the combination with a series of type-bars, of operating means therefor including a series of friction-couplers, one coupler for each type-bar, and a power-driven cylinder having a pair of peripheral friction-faces for each coupler operative to engage any coupler when presented by the depression of a key, said cylinder having means effective to establish 90 a working pressure operative to render the frictional engagement of the couplers with the cylinder effective to drive the couplers.
36. In a typewriting machine, the combination with a series of type-bars, of operating means therefor including a series of friction-couplers, one coupler for each type-bar, and a power-driven cylinder having a pair of peripheral friction-faces for each coupler operative to engage any coupler when presented by the depression of a key, said cylinder having means effective to establish 95 a working pressure operative to render the frictional engagement of the couplers with the cylinder effective to drive the couplers.
37. In a typewriting machine, the combination with a series of type-bars, of operating means therefor including a series of friction-couplers, one coupler for each type-bar, and a power-driven cylinder having a pair of peripheral friction-faces for each coupler operative to engage any coupler when presented by the depression of a key, said cylinder having means effective to establish 100 a working pressure operative to render the frictional engagement of the couplers with the cylinder effective to drive the couplers.
38. In a typewriting machine, the combination with a series of type-bars, of operating means therefor including a series of friction-couplers, one coupler for each type-bar, and a power-driven cylinder having a pair of peripheral friction-faces for each coupler operative to engage any coupler when presented by the depression of a key, said cylinder having means effective to establish 105 a working pressure operative to render the frictional engagement of the couplers with the cylinder effective to drive the couplers.
39. In a typewriting machine, the combination with a series of type-bars, of operating means therefor including a series of friction-couplers, one coupler for each type-bar, and a power-driven cylinder having a pair of peripheral friction-faces for each coupler operative to engage any coupler when presented by the depression of a key, said cylinder having means effective to establish 110 a working pressure operative to render the frictional engagement of the couplers with the cylinder effective to drive the couplers.
40. In a typewriting machine, the combination with a series of type-bars, of operating means therefor including a series of friction-couplers, one coupler for each type-bar, and a power-driven cylinder having a pair of peripheral friction-faces for each coupler operative to engage any coupler when presented by the depression of a key, said cylinder having means effective to establish 115 a working pressure operative to render the frictional engagement of the couplers with the cylinder effective to drive the couplers.
41. In a typewriting machine, the combination with a series of type-bars, of operating means therefor including a series of friction-couplers, one coupler for each type-bar, and a power-driven cylinder having a pair of peripheral friction-faces for each coupler operative to engage any coupler when presented by the depression of a key, said cylinder having means effective to establish 120 a working pressure operative to render the frictional engagement of the couplers with the cylinder effective to drive the couplers.
42. In a typewriting machine, the combination with a series of type-bars, of operating means therefor including a series of friction-couplers, one coupler for each type-bar, and a power-driven cylinder having a pair of peripheral friction-faces for each coupler operative to engage any coupler when presented by the depression of a key, said cylinder having means effective to establish 125 a working pressure operative to render the frictional engagement of the couplers with the cylinder effective to drive the couplers.
43. In a typewriting machine, the combination with a series of type-bars, of operating means therefor including a series of friction-couplers, one coupler for each type-bar, and a power-driven cylinder having a pair of peripheral friction-faces for each coupler operative to engage any coupler when presented by the depression of a key, said cylinder having means effective to establish 130 a working pressure operative to render the frictional engagement of the couplers with the cylinder effective to drive the couplers.

35. In a typewriting machine, the combination with a set of types and a set of reciprocatory tongues to operate said types, of a power-rotated driver, said tongues normally adjacent said rotating driver, said rotating driver having a set of peripheral V-grooves and said tongues having corresponding beveled sides, a set of keys, means to enable any key to set its tongue into co-operation with the corresponding groove in said rotating driver for frictional co-operation with said driver to actuate a type, each tongue being magnetically co-operable with said rotating driver to effect further contact of the tongue and driver for operating its type, and means for automatically disconnecting the tongue from the rotating driver and returning the tongue to normal position.

36. The combination of a power-revolved cylinder provided with a row of circumferential V-grooves, a row of clutch-tongues in the form of armatures adjacent to said cylinder, types operable by said tongues, keys individual to said tongues, and means to enable each key to move its tongue to a point sufficiently within reach of the magnetic influence of said revolving cylinder, to enable said cylinder to draw the tongue firmly into the adjacent groove, with force sufficient to cause the rotation of the cylinder to operate the tongue longitudinally and cause the type to print.

37. The combination of a power-revolved magnetized cylinder provided with a row of circumferential V-grooves, a row of clutch-tongues in the form of armatures adjacent to said cylinder, types operable by said tongues, keys individual to said tongues, means to enable each key to move its tongue to a point sufficiently within reach of the magnetic influence of said revolving cylinder, to enable said cylinder to draw the tongue firmly into the adjacent groove, with force sufficient to cause the rotation of the cylinder to operate the tongue longitudinally and cause the type to print, means for automatically disconnecting said each key from its tongue, and means for reconnecting the key thereto.

50 RICHARD VON REPPERT.
